UNITED STATES PATENT OFFICE.

GEORGE B. GLIDDEN, OF DIGHTON, MASSACHUSETTS, ASSIGNOR TO GEORGE FROST COMPANY, OF BOSTON, MASSACHUSETTS, A CORPORATION OF MASSACHUSETTS.

DESIGN FOR GARTER CLASP MEMBER.

Application filed September 11, 1922. Serial No. 3,675. Term of patent 14 years.

To all whom it may concern:

Be it known that I, GEORGE B. GLIDDEN, a citizen of the United States, residing in Dighton, in the county of Bristol and State of Massachusetts, have invented a new, original, and ornamental Design for a Garter Clasp Member, of which the following is a specification, reference being had to the accompanying drawing, forming part thereof.

The drawing is a perspective view of a garter clasp member embodying my design.

I claim—

The ornamental design for a garter clasp member, substantially as shown.

GEORGE B. GLIDDEN.
